United States Patent Office

Des. 213,375
Patented Feb. 25, 1969

213,375

ANTENNA

Harry R. Habig, 3531 Beldare Ave.,
Cincinnati, Ohio 45220

Filed Nov. 2, 1967, Ser. No. 9,249

Term of patent 14 years

U.S. Cl. D26—14
Int. Cl. D14—03

FIG. 4

FIG. 1

FIG. 3

FIG. 2

FIG. 1 is a top view of an assembly embodying my basic antenna design;

FIG. 2 is an end elevation view thereof;

FIG. 3 is a side elevation thereof; and

FIG. 4 is a perspective view thereof.

I claim:

The ornamental design for an antenna, substantially as shown and described.
